CLAIM

The ornamental design for a bottle sleeve, as shown and described.

DESCRIPTION

FIG. 1 is a front elevational view of a bottle sleeve, showing my new design;

FIG. 2 is a top left front perspective view thereof;

FIG. 3 is a left side elevational view thereof, the right side elevational view being a mirror image;

FIG. 4 is a top plan view thereof;

FIG. 5 is a bottom plan view thereof;

FIG. 6 is a front elevational view thereof, shown in condition of use; and,

FIG. 7 is a top left perspective view thereof, shown in condition of use.

In the drawings, the broken lines depict unclaimed subject matter only and form no part of the claimed design.
